UNITED STATES PATENT OFFICE

EARLE C. PIPER, OF COLUMBUS, OHIO, ASSIGNOR TO THE LUBRETOR COMPANY, OF COLUMBUS, OHIO, A CORPORATION OF OHIO

LUBRICATING SYSTEM FOR INTERNAL COMBUSTION ENGINES

Application filed May 29, 1929. Serial No. 367,068.

This invention relates to an auxiliary lubricating system designed for use in connection with internal combustion engines and by means of which a limited supply of a lubricant may be delivered to the explosion chambers of an engine so as to effect what is known as upper cylinder lubrication.

In accordance with the present invention an auxiliary lubricating system is provided consisting of a lubricant reservoir located extraneously of the engine with which the system is connected, there being a conduit leading from said reservoir to an automatic regulator mounted in connection with the fuel intake conduit of said engine. The construction of the regulator being such as to admit automatically of the flow of the lubricant from said reservoir and into the fuel inlet conduit and thence to the explosion chambers of the engine in accordance with the actual operating requirements of the engine, advantage being taken of the fluctuating vacuum or suction within the intake conduit to control the action of the regulator to effect the introduction of the auxiliary lubricant into said engine in desired quantities.

Among the objects of the invention are: The provision of a normally sealed lubricant container or reservoir in which the supply of the auxiliary lubricant is received, and whereby through the construction and mounting of the container a definite grade of lubricant may be assured in the operation of the system; in constructing the regulator so as to provide a sensitive yet positive valve means therein which is responsive directly to the suction in the fuel inlet conduit so that when the associated engine is moving under a full load and is receiving its maximum fuel supply by reason of the throttle being wide open and a moderate vacuum produced in said conduit, the valve means of the regulator will be opened to its fullest extent so as to allow for the maximum inflow of the lubricant into said conduit, but whereby upon the closing of the throttle more or less, as when the engine is running idle or under a light load, and the vacuum in the conduit increased, said valve means will respond to more completely obstruct the flow of the lu-

bricant to said conduit, and whereby when the operation of the engine is arrested altogether, said valve means will assume a position completely arresting lubricant flow into said conduit, the operation of the regulator being such as to provide for the automatic operation of the system after installation and to require no further manual attention other than maintaining a desired quantity of the lubricant in the removable container or reservoir.

I am aware of the fact that systems of this kind have been proposed heretofore and hence it is a further object of the present invention to provide a system of this kind of improved and simplified construction, of more positive operation and of more economical construction than any other system of this type of which I am now aware.

For a further understanding of the invention reference is to be had to the following description and the accompanying drawings, in which:

Figure 1 is a side elevation of an internal combustion engine disclosing the application of the auxiliary lubricating system comprising the present invention thereto.

Figure 2 is a vertical sectional view disclosing more particularly the construction of the lubricant receiving container and mounting used in connection with the system.

Figure 3 is a front elevation of the structure disclosed in Figure 2,

Figure 4 is a top plan view thereof,

Figure 5 is a detail side elevation disclosing the mounting in an open position permitting of the substitution or removal of the lubricant container,

Figure 6 is a horizontal sectional view taken on the line 6—6 of Figure 2,

Figure 7 is a greatly enlarged vertical sectional view taken through the automatic regulator employed by the present invention, and

Figure 8 is a horizontal sectional view on the line 8—8 of Figure 7.

Referring more particularly to the accompanying drawings, the numeral 1 designates generally an internal combustion engine of,

for example, the type employed in connection with motor vehicles. The engine is provided with the usual fuel inlet conduit or intake manifold 2 to which is connected any standard type of carburetter 3. The conduit 2 is provided with the usual throttle valve 4 for controlling the inflow of the carburetted fuel into the explosion chambers of the engine cylinders.

The purpose of the present invention, as above stated, is to provide a system, operated independently of the usual oiling mechanism of the engine, for introducing an auxiliary supply of a lubricant into the explosion chambers of the engine for effecting lubrication of this ordinarily neglected part of the engine. The advantages of proper cylinder lubrication are thoroughly well understood at this time and therefore need not be elaborated upon at this time, but in general such lubrication provides for a more smoothly operating engine, reducing friction between pistons and cylinder walls, the proper seating and control movement of the inlet and exhaust valves and the elimination of hardened carbon deposit on the cylinder walls, valve seats, valves and other surfaces in and communicating with the explosion chambers. It will be observed that this system is auxiliary to the main circulation of oil through the engine and its purpose is to provide for adequate lubrication of parts which can not be lubricated by the usual oil pumping means of an explosive engine.

Therefore, the system comprises broadly an oil container 5 preferably mounted at an elevated position with respect to the engine and, for convenience in connection with the foot board or cowl construction 6 of a motor vehicle. Leading from the bottom of the container 5 is a conduit 7, preferably of copper tubing, which has its lower end connected with an automatic regulator 8, which has been shown in detail in Figure 7, and is connected with the intake conduit 2 so that the lubricant drawn from the container 5 will be discharged into the fuel mixture passing through the conduit 2 and thence delivered to the engine cylinders.

An important feature of the present invention resides in the specific construction of the regulator 8 which is so formed as to admit the auxiliary lubricant into the engine in proportion to the real demand of the latter, that is, a greater supply when the engine is operating under approximately full load conditions, and a diminished supply when the engine is running idly or under a comparatively light load. In securing this end the regulator is formed to include a metallic casing 9 in which is provided a vertically disposed longitudinally extending chamber 10. The bottom of this chamber is threaded and closed by means of a plug or cap 11 having an axially disposed vent opening 12. The oppo-

site end of the chamber 10 is threaded for the reception of a plug 13, which includes an upstanding threaded nipple 14 adapted to constitute a seat for the reception of the lower end of the conduit 7. A threaded nut 15 is carried by the nipple 14 and engages with the reversely inclined head 16 fixed upon the lower end of the conduit 7 for the purpose of securely retaining said conduit and nipple in secured relationship, preventing loss of the lubricant and avoiding the necessity of a flexible packing.

The plug 13 is provided with a longitudinal bore 17 threaded at its lower end for the reception of a sleeve 18. The bore of this sleeve is provided at a part midway of its length with a valve seat 19 upon which there normally rests a ball valve 20 operating by gravity. The sleeve 18 carries a transverse pin 21 above the valve 20 so as to confine the movements of the latter between said pin and the seat 19. Normally when the engine is not running the valve 20 occupies its seated position and prevents the flow of the lubricant from the container 5 into the chamber 10.

Slidably mounted in the bottom of the chamber 10 is a piston 22, which is internally chambered as at 23 for the reception of the body 24 of a needle valve 25. The top of the chamber 23 is threaded for the reception of a guide bushing 26, and a coil spring 27 is situated between the body 24 and the bottom of the piston 22 so as to normally maintain the needle valve in a resiliently extended position. The top of the needle valve terminates in a conoidal tip 28 which is situated in registration with the bore in the sleeve 18, whereby when the piston 22 responds to vacuum or suction conditions within the conduit 2 and moves upwardly in the chamber 23, the tip 28 of the needle valve will engage with the ball valve and move the latter from its seat allowing under normal conditions of engine operation, the lubricant to flow past the valve and into the chamber 10. Further upward movement of the piston results in causing the stem of the needle valve to completely occupy and fill the lower part of the sleeve 18, with the result of obstructing further oil flow into the casing 9 or chamber 10. It will be observed that the regulator provides for the arresting of the oil flow under two conditions, one, when the engine is idle and no suction is created and two, when the engine is throttled and an extreme vacuum is produced in the conduit 2. Any intermediate condition between these two extremes permits of a graduated quantity of the lubricant to flow into the chamber 10 and thence into the conduit 2 by way of the bores 29 provided in the horizontally extending fittings 30 connected with the side of the casing 9. It will be observed that the outer fitting 30 is threaded as at 31 into the

wall of the fuel intake manifold and projects some distance into said manifold so as to be spaced from the walls thereof. This construction makes for an improved release 5 of the oil globules from the fittings 30 and the efficient entrainment thereof with the fuel gases. Preferably, a spring 32 is interposed between the lower part of the nipple 14 and the upper part of the piston 22 and 10 tends to maintain the piston in the lower part of the chamber 10.

As before stated, when an engine is moving under a full load and is receiving its maximum fuel supply by reason of the 15 throttle valve 4 being substantially wide open only a moderate vacuum is produced in the intake manifold or conduit of the engine, inasmuch as the suction of the piston of the engine at this time will draw the fuel 20 freely through the intake into the cylinders preparatory to firing the same. Thus under these conditions of moderate vacuum the needle valve has its conoidal tip 28 engaging with the ball valve 20 so as to elevate the lat- 25 ter from its seat 19, but the needle valve is not extended into the bore 17 of the sleeve 18 to an extent sufficient to completely obstruct the flow of the oil. This condition occurs to a wide range of engine operation and as 30 the vacuum increases or decreases corresponding adjustment is made in the position of the needle valve to regulate the oil flow. However, upon closing the throttle valve 4 more or less when the engine is running idle 35 or under a light load the admission of fuel into the intake is cut off or reduced accordingly, thereby increasing the vacuum within the intake conduit by reason of the reciproca- 40 tion of the pistons in the cylinders. Since the engine is operating more slowly under this latter condition and therefore the demand for the oil is accordingly lessened, the increased suction results in raising the piston 22 to such an extent that the diameter of 45 the stem of the needle valve 25 completely fills the lower portion of the bore 17 and cuts off the flow of the auxiliary lubricant substantially completely if necessary. Thus the invention provides a very positively acting 50 automatic regulator of extremely simple yet sensitive construction which assures the introduction of the correct amount of the auxiliary lubricant into the engine cylinders. While I am aware of the fact that this broad 55 principle of operation has been proposed in other prior systems yet to the best of my knowledge the prior art does not contain as corresponding constructional advantages.

Another very important feature of the 60 present invention resides in the construction of the container 5 and the manner of mounting the same. The mounting for the container is designated generally by the numeral 33, and consists of a base member 34 which is 65 connected as at 35 with a vertically extending

strap 36, the latter being bolted or otherwise secured as at 37 to the foot board 6. The base member is provided with a well 38 in which is received the neck 39 of the container 5 when the latter is inverted and applied to the mounting for use. The neck 39 includes a penetrable cap 40 which normally seals the contents of the container and provides a method of identifying the lubricant used. This is a very important feature in the use of 70 the system since it has been found by experiment that the system operates to the best advantage with certain grades of oils but not with others and therefore it is to the advantage of the user to be sure of obtaining 75 the grade of lubricant recommended by the manufacturer for use in the system.

The base member 34 is provided with an up- 80 standing threaded prong 41 whereby when the container is applied to the system so that the neck thereof rests upon the annular gasket 42 surrounding the perimeter of the well 38, the cap 40 will be penetrated by the prong 41, which results in producing an opening in said cap through which the oil may flow slowly 85 from the container and into the bottom of the well 38, filling the latter with the lubricant up to the level indicated at 43, at which point further rise of the oil is prevented by air pressure and the vacuum produced in 90 the container or bottle. The well is provided with a vent tube 44 which preferably terminates in a downturned portion to prevent clogging. As the oil is drawn out from the bottom of the well and the level lowered additional 95 oil is withdrawn from the container and air allowed to enter the interior of the latter until the level is restored in said well.

To hold the container in its applied position the top of the strap 36 has pivoted there- 100 to the arm of a pressure plate 45. This plate is provided centrally with an ear 46 to which is pivoted a locking lever 47. The shorter leg of this lever is notched as at 48 for en- 105 gagement with the upper edge of a bail 49, the latter being pivotally mounted as at 50 in connection with the lower part of the base member 34. It will be seen that by swinging the lever 47 to the position shown in Figure 2 the bail 49 will be placed under tension 110 so as to hold the plate 45 in close frictional relationship with the upper end of the bottle or container 5. Since the shorter leg of the lever 47 is swung off-center it will be seen that the lever 47 will be locked in this position. Thus, 115 through the mere actuation of the lever 47 the container 5 may be applied to or removed from the mounting with very considerable ease and convenience. In past systems of this kind the container has been formed from 120 metal and permanently mounted in connection with the vehicle. This method has the disadvantage of permitting of the use of any grade of a lubricant in the system without 125 reference to the quality and characteristics 130

thereof. This is all avoided by the present invention wherein the sealed and removable container is provided. Again, by forming the container from glass the quantity of the lubricant carried thereby may be readily noted at any time thus preventing the system from running dry with consequent harmful results. The base member 34 is provided with an outlet port 51 leading from the well 38 to the conduit 7. Preferably, the entrance 10 of this port is covered by a screen 52 for the purpose of excluding foreign matter and preventing the clogging of the valve passages of the regulator.

15. What is claimed is:

1. In an auxiliary lubricating system for internal combustion engines, a support formed to include a lubricant receiving well, an inverted lubricant containing bottle having the neck portion thereof positioned within said well and spaced from the bottom thereof, a penetrable cap closing the neck of said bottle, means in the bottom of said well for penetrating said cap and establishing 25 communication between the interior of said bottle and said well, clamping means for removably holding the bottle in connection with said support, and a conduit leading from the bottom of said well to the fuel intake passageway of an associated engine.

2. In an auxiliary lubricating system for internal combustion engines, a fixed support formed to include a well, a bottle carried by said support in inverted order with the neck 35 of said bottle positioned within said well and spaced from the bottom thereof, a gasket between said supporting member and the neck of said bottle, clamping means carried by said support for removably holding said bottle in a firmly seated position upon said gasket, the neck of said bottle being closed normally by a penetrable cap, a pointed member 40 stationarily positioned in the bottom of said well and adapted to penetrate said cap when said bottle is operatively seated upon said gasket, said member serving to produce an opening in said cap and to establish lubricant flow from said bottle into said well and to maintain a substantially constant oil level 45 in said well, and a conduit leading from said well to the fuel intake passageway of an associated engine.

3. In an auxiliary lubricating system for internal combustion engines, a support including a reservoir, a lubricant receiving bottle having the neck portion thereof positioned within said reservoir and spaced from the bottom of the latter and operative to maintain a substantially constant fluid level 55 within said reservoir, a clamping plate pivoted to said support and arranged to engage the upper part of said bottle when the latter is in an applied position, a swinging bail carried by said support, and a clamping 60 lever pivotally carried by said plate and co-

operative with said bail to hold said bottle by compression in its applied position.

4. A device of the character set forth comprising a support including a reservoir, a liquid containing bottle having the neck portion thereof positioned within said reservoir and spaced from the bottom of the latter and operative to maintain a substantially constant fluid level within said reservoir, a clamping plate pivoted to said support and 70 arranged to engage the upper part of said bottle when the latter is in an applied position, a swinging bail carried by said support, and a clamping lever pivotally carried by said plate and cooperative with said bail to 75 hold said bottle by compression in its applied position.

5. A device of the character set forth comprising a support formed to include a fluid receiving well, an inverted fluid containing 85 bottle having a neck portion thereof positioned within said well and spaced from the bottom thereof, a penetrable cap closing the neck of said bottle, means in the bottom of said well for penetrating said cap and establishing 90 communication between the interior of said bottle and said well, clamping means for removably holding a bottle in connection with said support, and a conduit leading from the bottom of said well.

In testimony whereof I affix my signature.
EARLE C. PIPER.
